(57) CLAIM

The ornamental design for a golf club head cover with integral aperatures therefor, as shown and described.

DESCRIPTION

FIG. 1 is a perspective view of a golf club head cover with integral aperatures therefor showing my new design thereof; FIG. 2 is a front elevational view thereof; FIG. 3 is a bottom elevational view thereof; FIG. 4 is a left side elevational view thereof; and, FIG. 5 is a right side elevational view thereof.

The rear elevational view is a mirror image of the front elevational view shown in FIG. 2 thereof.

The top elevational view is a mirror image of the bottom elevational view shown in FIG. 3 thereof.
